US00D329602S

United States Patent [19]
Cochrane

[11] **Patent Number:** **Des. 329,602**
[45] **Date of Patent:** **** Sep. 22, 1992**

[54] **BOTTLE CLOSURE**

[76] Inventor: **Benjamin A. Cochrane, 181 Sonora Ave., Danville, Calif. 94526**

[**] Term: **14 Years**

[21] Appl. No.: **368,428**

[22] Filed: **Jun. 19, 1989**

[52] U.S. Cl. **D9/435; D9/454**
[58] Field of Search **D9/435, 445, 454; 215/324, 340, 353**
